CLAIM

The ornamental design for a window cornice panel, as shown and described.

DESCRIPTION

FIG. 1 is a front elevational view of a window cornice panel showing my new design;

FIG. 2 is a left side elevational view, with the right side elevational view being a mirror image thereof;

FIG. 3 is a top plan view thereof;

FIG. 4 is a bottom plan view thereof; and,

FIG. 5 is a rear elevational view thereof.

The cross hatching in FIGS. 1, 2, 3, and 4 representing fabric is understood to continue uniformly along the entire surface of the fabric.
